UNITED STATES PATENT OFFICE.

LESLIE STEVENS, OF GLEN RIDGE, NEW JERSEY.

MACHINE FOR SHAPING HATS.

1,070,745.

Specification of Letters Patent. Patented Aug. 19, 1913.

Application filed September 2, 1909. Serial No. 515,912.

To all whom it may concern:

Be it known that I, LESLIE STEVENS, a citizen of the United States, residing at Glen Ridge, county of Essex, and State of New Jersey, have invented certain new and useful Improvements in Machines for Shaping Hats, fully described and represented in the following specification and the accompanying drawings, forming a part of the same.

This invention relates to a machine or apparatus for shaping hats, and especially for shaping hats from felt or other suitable stretchable and moldable material, and, although broadly applicable to the shaping of hats of other forms, the invention is more particularly adapted and intended for shaping one-piece hats of the class or general shape known as extension-crown hats, that is, hats having a head opening smaller than the lower part of the crown, such smaller head opening in one-piece hats being formed by folding the felt or other material of which the hat is formed inward from the lower extremity of the crown and from the brim, and in some of its features the invention relates expressly to machines for forming hats of this kind.

The object of the invention is generally to provide a machine whereby hats, and especially one-piece extension-crown felt hats, may be produced more rapidly, with greater economy, and of superior quality than has been possible with the machines heretofore in use.

In shaping hats from felt or other bodies or blanks, it is necessary that the body be first steamed or otherwise treated to soften the felt or other material before being stretched or pressed to shape, and that before the shaped hat is removed from the block or die or other shaping devices the stiffening be caused or allowed to set or harden again sufficiently so that the hat will retain its shape. This necessary treatment to soften and then reharden the felt or other material has added greatly to the difficulty, the time required, and the expense of shaping of hats, and this has been especially the case in the shaping of hats of the class above referred to having the material folded inward to form a head opening smaller than the lower part of the crown. In fact, it has been impossible before my invention to shape hats of this kind otherwise than by handwork, and the process has been slow,

laborious and expensive and the results unsatisfactory. By my invention, delays and expense caused by the necessity of softening and then rehardening the felt are very largely reduced, and the difficulties heretofore met with in the shaping of hats of all shapes are practically eliminated, and the invention makes it possible to shape hats of the class above referred to as easily by machine as it has heretofore been possible to shape hats of ordinary shape having the head opening the full size of the lower part of the crown.

In shaping hats in a machine constructed in accordance with the invention and embodying the various features thereof in the preferred form, the hat body, having been first softened or not as desired, is placed in the machine in position to be shaped and is then subjected to the softening action of steam, and when it has become sufficiently soft and while still kept soft by steam, is stretched to the desired shape, and is then, while still held in shape by the shaping devices, subjected to the drying and cooling action of a current of cool air until the stiffening material or substance has become sufficiently set and the hat dried and sufficiently hardened to hold its shape. In forming extension crown hats, the edges of the hat body or blank are held by suitable circularly arranged clamping or holding means, and after the body or blank has been sufficiently softened by the action of the steam, a forming block is pressed into the central or crown portion thereof and the material is stretched about the block and folded inward over the outer face or base of the block by suitable means to form the head band smaller than the adjacent part of the crown. During the time that the hat is being stretched over the block and inward from the brim clamps, the steaming may be and preferably will be continued. Then when the hat has been stretched to shape, the steam is shut off, the hat is subjected to the drying and cooling action of a current of cool air until the stiffening material becomes sufficiently set and the hat sufficiently hardened to hold its shape. It is then removed from the apparatus complete, except for the finishing operations or further shaping of the brim if that is desired.

The whole operation takes but a very short time. Usually about thirty seconds steaming will properly soften a felt hat body, and

about three minutes will be sufficient to dry and harden the hat by means of a blast or current of air at normal room temperature.

The invention comprises various features 5 of construction, arrangement and combination of parts whereby hats may be made rapidly and economically and of superior quality.

A full understanding of the invention can 10 best be given by a detailed description of the construction and operation of a machine and a modification thereof embodying the various features of the invention, in the preferred form, and such a description will 15 be given in connection with the accompanying drawings, in which—

Figure 1 is a side elevation of a machine for making one-piece extension crown felt hats. Fig. 2 is a front elevation of the machine shown in Fig. 1. Fig. 3 is a plan view of the upper part of the machine. Fig. 4 is a section on line 4 of Fig. 1. Fig. 5 is a section on line 5 of Fig. 7, but on the scale of Figs. 1 to 4. Fig. 6 is a section on line 6 of Fig. 7, but on the scale of Figs. 1 to 4. Fig. 7 is a section on line 7 of Figs. 1 and 3, but on an enlarged scale. Fig. 8 is a section similar to Fig. 7 but with the lower part of the steaming and drying box broken away and showing the upper clamping member and the shaping block and block plunger in their lowered position, and with the folding plates moved inward to stretch the hat about the block. Fig. 9 is a view similar to Fig. 8, but showing the use of a forming block provided with a forming shoulder on its outer face or base against which the inward fold of the felt is pressed in forming the head opening of the hat. Fig. 10 is a view similar to Figs. 8 and 9, but showing the machine as used for shaping hats having a head opening of the full size of the crown. Fig. 11 is a diagram showing an extension crown hat of the shape produced by the machine when a block of the shape shown in Figs. 8 and 9 is used. Figs. 12 and 13 are similar diagrams, showing examples of other forms of hats which may be produced with the machine shown by using properly shaped forming blocks. Fig. 14 is a similar diagram of a hat having a head opening of the full size of the lower part of the crown, such as is produced by the machine when used as illustrated in Fig. 10.

Referring to the drawings, and first to Figs. 1 to 6; the various operative parts of the machine are carried by two side frames 10. Supported between and above the upper ends of the side frames, is a table or bed 11 which in the machine shown is mounted to have parallel upward and downward movement by being carried by arms 12 mounted on shafts 13, which are connected as to rock together by a link 14 extending

between outside arms 15 on the shafts 13, one of which outside arms is extended to form an operating handle 16. By throwing the handle 16 forward from the position shown in Fig. 1, the table 11 may be moved forward and downward from the position shown in Fig. 1 so as to bring it into convenient position for the placing and removal of blanks and hats when the machine is to be used as an ordinary stamping machine. 75 When so used the steaming and drying box and parts connected therewith hereinafter described will, of course, be removed. When such parts are in place and the machine is intended to be used for carrying out my 80 improved process, the table 11 will remain at all times in the position shown in Fig. 1 in which position it is held by resting on stops 17, the carrying arms 12 being thrown back past the vertical. 85

Mounted on the table 11, are parts which with the table form a steaming and drying box or chamber A, such parts being a short sheet metal cylindrical shell 20 set on the table and a top plate 21 set on the shell. 90 The table 11 and the top plate 21 are formed with flanges which extend inside the walls of the shell 20, and the shell and top plate are secured and held in place by means of tie rods 22. A cover plate 23 is mounted 95 on the plate 21, and the plates 21 and 23 are each formed with a central opening of sufficient size to permit a hat body and a shaping form or block of the largest size with which the machine is intended to be operated to 100 be passed down through the openings into the chamber A. The plate 21 is also cut away on its upper face to form a guide-way in which are mounted two oppositely reciprocating and overlapping folding plates 105 24 and 25. These folding plates are each cut away from their inner ends to form folding jaws having tapering or inclined folding edges c extending out from the inner ends of the plates and having folding and shaping edges b connecting the inclined folding edges c, which edges c when the plates are 110 in their inner position form an opening corresponding to the outside dimensions of the inward fold which is to form the head opening 115 of the hat. The folding plates normally lie in their outward position, as shown in Figs. 2, 3, 4 and 7, in which position the inclined jaws c of the plates overlap, but the jaws recede 120 from the top of the steaming and drying box when the introduction of the hat body and cover plate A. The folding plates are properly held by means of a link 125 through a cam or cam-shaft lever 130 and link 131, the lever 130 being each connected at one end with one of the folding plates, being respectively mounted on carrying links or supports 132, and being connected beyond the point of connection to the sup- 130

ports with the links 28, by which they are connected to the hand lever 26. When the lever 26 is thrown from the position shown in Figs. 1 to 4 to that shown in Fig. 5, the 5 folding plates will be moved inward to the position shown in Figs. 5 and 8, and as the plates approach the end of their inward or folding movement the force with which they are moved will increase on account of 10 the toggle-like connection between the lever 26 and the levers 27.

In order that the machine may be used for shaping hats with head openings of different sizes and shapes, means are provided 15 for varying the amount of inward movement of the folding plates, and the plates are mounted in the machine so as to be readily removable to permit plates having folding edges δ of different shapes to be 20 used in the machine. For adjusting the inward movement of the folding plates, the links 29 are made adjustable in length; and the plates are readily removed and replaced in the machine by simply disconnecting the 25 levers 27 from the plates and removing the cover plate 23 so that the folding plates may then be lifted out of the guide-way in the top plate 21.

The cover plate 23 forms the lower member 30 of a clamping means by which the edges of the hat body are held during the shaping operation. The upper member of such clamping means is formed by an annular plate 30 which is carried by rods 31 depending from a cross-head 32 which is carried by a pair of vertical sliding rods 33 mounted in bearings in the side frames 10. The cross-head is mounted so as to be capable of vertical adjustment on the rods 33 as 40 shown in Fig. 2, and the supporting rods 31 are also adjustably mounted in the cross-head to provide for accurate leveling and adjustment of the plate 30.

The annular clamping plate 30 is preferably of an internal diameter slightly less than the diameter of the brim of the smallest size hat to be shaped by the machine, and is preferably provided on its under side with a wooden facing 35 so as to avoid contact with the material of the hat of the metal of which the clamping plate is preferably formed. The cover plate 23 which forms the lower clamping plate will also preferably be made of metal, and to avoid 55 contact therewith of the hat material, it is covered by a sheet 36 of felt or other suitable material formed with a central opening of such a size that the inner edges of the felt will extend over the inner edge of the plate 23. The edges of the hat body might be clamped directly between the upper clamping plate and the layer of felt lying on the lower clamping plate 23, but in order 60 to reduce the width of the portion of the hat body which is held between the clamp-

ing plates, a series of flat rings 37 preferably of rubber or other suitable yielding elastic material are laid on the felt 36. Three such rings are shown in the drawings, but it will be understood that a greater 70 number of rings might be used, and that one or more of the rings will be removed, according to the diameter of the brim of the hat which is to be shaped by the machine. A flange 38 is provided at the edge of the 75 plate 23 to hold the felt 36 and the rubber rings 37 in position. By making these gripping rings 37 of rubber or other suitable yielding elastic material, not only is a grip on a small area of the hat body provided 80 for, but a positive grip throughout the length of the clamping means is secured.

The rods 33 are normally held in the position shown in Figs. 1 and 2 with the clamping plate 30 in its raised position by 85 springs 40, and are moved downward against the tension of the springs 40 to lower the cross head and clamping plate by means of a foot treadle 41 which is connected by a link 42 with a lever 43 pivotally 90 mounted on a support 44 and having its free end connected by a link 45 with a cross-bar 46 extending between the lower ends of the rods 33. When the treadle has been depressed to carry the clamping 95 plate 30 down into operative position, it is held by a catch 39 to lock the cross head and clamping plate against upward movement. A hand lever 47 is also provided by which the rods 33 may be operated to lower 100 the clamping plate 30 from its normal or raised position, but which is especially intended for increasing the downward strain on the cross-head and upper clamping plate when they have been brought to their lower 105 or operative position. This hand lever 47 is fast on a shaft 48 mounted in bearings at the ends of the cross bar 46, and which shaft 48 carries at each end an arm 49 which is pivotally connected to one end of a link 50, 110 the other end of which is pivoted to one of the side frames. When the hand lever 47 is thrown over to the left from the position shown in Fig. 1, therefore, the rods 33 will be forced downward by the action of the 115 arms 49 and links 50, and similarly, if the rods 33 are thrown downward by the depression of the treadle 41, the hand lever 47 will be thrown over to the left from the position shown in Fig. 1; and when the rods 120 33 have been given about their full downward movement, the arms 49 and links 50 will have been brought into a position in which they stand almost in line with each other, so that a comparatively slight force 125 applied to the hand lever 47 will cause a very strong downward pull to be exerted on the rods 33 and a very strong pressure to be brought to bear on the upper clamping plate so as to insure a positive and power- 130

ful gripping of the edges of the hat body between the upper and lower clamping plates.

A plunger rod 51 is mounted to slide vertically in bearings located centrally of the cross head 32 and carries at its lower end a plunger head 52 for pressing the crown form or block down into the hat body. The plunger head is preferably adjustable on the rod, as by being secured in place thereon by a set screw as shown. The plunger rod is connected at its upper end to a hand lever 53 pivoted at one side of the cross head, and the plunger rod and lever are normally held in position to hold the plunger raised up to the position indicated by dotted lines in Fig. 1 by means of a weight 54 or other suitable means. The plunger 52 is depressed to force the forming block downward by throwing the lever 53 downward to the position shown by dotted lines in Fig. 1, and is held in that position by means of a hook 55 under which the lever is adapted to be engaged.

Steam is admitted to the steaming and drying chamber through a steam inlet 60 at the bottom of the chamber which connects with a supply pipe 61, and the supply of steam to the chamber is controlled by a valve 62. Means are provided for causing the steam to be properly diffused as it enters the chamber A, and for this purpose a diffusing cap 63 may be provided. A drip pipe 64 is provided for carrying away any water of condensation which may collect in the chamber.

The setting and drying current of cool air is admitted to the steaming and drying chamber from an air supply pipe 70 through an inlet opening 71 in the side wall of the chamber, and the admission of air is controlled by means of a valve or shutter plate 72 mounted to slide on the inner side of the side wall of the chamber and having an inlet port 73, and which may be shifted to bring the port 73 opposite the inlet opening 71 to admit air, or to bring a solid portion of the plate opposite the inlet opening to cut off the air blast, as desired, by means of an operating rod 74 which extends through the side wall of the chamber and is provided with a handle in a position to be reached by the operator. An air outlet opening 75 is also provided in the wall of the chamber A, which is also controlled by the shutter plate 72 which has a port 76 in position to register with the outlet opening 75 when the port 73 registers with the inlet opening 71. The air circulating through the chamber serves to cool and dry the crown of the shaped hat. For cooling and drying the brim of the hat, a blast of air is caused to blow downward on the brim through the central opening of the annular clamping plate 30. To provide such blast a branch

80 from the air supply pipe 70 is arranged to direct a blast of air downward on to the brim of the hat and the inner fold which forms the head opening. This branch pipe, or blast nozzle, 80 is provided with a suitable valve 81 having a handle within convenient reach of the operator.

In the operation of the machine, the parts being in the positions shown in Figs. 1 to 4, the hat blank or body is placed in position with the edge of the body extending out over the inner rubber ring on the lower clamping plate 23 and with its central portion extending down into the steaming and drying chamber A; and the upper clamping plate 30 is then moved down to clamp the edge of the hat body between the clamping plates as shown in Fig. 8. The valve 62 is then opened to admit steam to the chamber A, and a crown form or block of suitable shape and size, according to the shape and size to which the crown of the hat is to be shaped, is inserted beneath the plunger 52 into the hat body, and the hand lever 53 is operated to depress the plunger 52 and force the forming block down to the position shown in Fig. 8, in which the outer face or base of the block is just below the plane of movement of the folding plates. The end of the plunger rod 51 projecting down below the bottom face of the plunger will enter a central hole in the forming block, as indicated by dotted lines in Fig. 8, to center the block beneath the plunger. The insertion and positioning of the forming block may take place while the hat body is being softened by the steam admitted to the chamber A. As will be seen from Fig. 8, the steam admitted to the chamber A will reach all parts of the hat body except the small portion at the edge thereof which lies between the upper and lower clamping plates. After the hat body has become sufficiently softened, the hand lever 53 is thrown over from the position shown in Figs. 1 to 4 to that shown in Fig. 5, thereby moving the folding plates 24 and 25 inward to stretch the felt inward over the forming block. The steam is then shut off, and the rod 74 is drawn outward to open the inlet 71 to admit air from the pipe 70 to the chamber A and to open the outlet 75 to permit the steam in the chamber and then the air to escape, and the valve 81 controlling the blast of air from pipe 80 is also opened. The cool air circulating through the chamber A will quickly set and dry the crown portion of the hat, and the blast from the pipe 80 will at the same time set and dry the brim and head band portion of the hat. The hat will thus become quickly set and hardened while held to shape in the machine. After the hat has become sufficiently set and hardened, the air blasts are cut off and the folding plates are retracted by 130

throwing the hand lever 26 back to the position shown in Figs. 1 to 4 and the cross head 32 is allowed to rise to raise the upper clamping member and the plunger, and the 5 formed hat with the forming block still in it may then be removed from the machine.

It will be observed that in shaping a hat as above described the felt or other material of which the hat is formed is subjected to 10 the softening action of steam and thereby kept soft, mellow and elastic during the entire shaping operation; that the hat is then set in the shape to which it has been stretched and thoroughly dried while still 15 held in shape by the shaping devices; and that when taken from the machine the hat will be shaped, set and dried and all ready for the finishing operations, without waiting for further drying. Delay and expense 20 incident to putting the hats through a drying operation is thus avoided, and the forming blocks may be removed from the hats as soon as they are taken from the machine, thus avoiding the necessity of employing a 25 great number of forming blocks, as is required when the blocks have to remain in the hats during the usual drying of the hats in a drier or otherwise.

The brim of the hat may be left flat or 30 may be subsequently shaped as desired in any suitable way. The slight flare which the brim will have when the hat is taken from the machine may be easily removed and the brim made flat by simply setting 35 the hat, brim down, with the block still in it on a suitable flat surface which may be slightly heated if desired.

The size and shape of the crown of hats formed in the machine will, as above stated, 40 depend upon the size and shape of the forming block used, and a forming block of almost any desired shape may be used. In shaping hats with head openings smaller than the largest part of the crown, a sectional forming block of any suitable construction will be used, as for example, a block such as described in my application 45 for U. S. Patent No. 495,898, filed May 14, 1909. Folding plates 24 and 25 having 50 folding edges *b* of different shapes will be used and the inward movement of the folding plates will be adjusted through the adjustable links 29, as hereinabove described, according to the size and shape of the head 55 opening of the hats to be made. Fig. 11 shows the shape of a hat produced by the machine when a block of the shape shown in Figs. 8 and 9 is used, and Figs. 12 and 13 show hats which are examples of other 60 shapes which might be produced on the machine by merely using different shape blocks.

When a forming block with a flat outer face or base is used in the machine for forming extension crown hats, there is an advantage in using a plunger head 52 having its

lower part or pressing plate of the size and shape of the inside of the head opening of the hat to be formed, so that in the operation of the machine when the folding plates are moved inward the inward fold of the felt 70 or other material will be pressed by the folding plates against the peripheral face or edge of the plunger, thus not only securing a better formation of the fold which forms the head opening, but also causing 75 the forming block to be positively centered by the folding plates and thus insuring the proper relative position of the head band and crown of the hat. When the peripheral face or edge of the plunger is to serve thus 80 as a forming shoulder to coact with the folding plates in forming the inner fold or head band of the hat, plungers of the proper size and shape will be attached to the plunger rod according to the size and shape of the 85 head openings of the hats to be shaped. Instead of using a forming block with a flat outer face, however, a block having a forming shoulder projecting from the outer face thereof, as shown and described in my said 90 application is preferably used in the machine. As will be clear from an inspection of Fig. 9, the operation of the machine with a block of this kind will be the same as when 95 a block with a flat outer face is employed, except that the forming shoulder 90 of the block will coöperate with the folding plates 24 and 25 in forming the head opening of the hat and in centering the block.

When it is desired to use the machine in forming hats having a head opening of the full size of the greatest diameter of the crown, it is not necessary to make use of the folding plates 24 and 25, as the hat may be shaped by simply clamping the edge of the material forming the hat body between the clamping plates 23 and 30, and then forcing the forming block down into the crown of the hat through an opening of the proper size and shape corresponding to the 100 size and shape of the head band or head opening of the hat. To adapt the machine for shaping hats in this way, a size ring 95 is set on the plate, as shown in Fig. 10, and in order to insure the proper positioning of 105 the size ring the inner edge of the plate 23 is cut away or rabbeted, as shown at 96. In operating the machine with the size ring in use, the size ring being in position, the hat body or blank will be placed in the machine 110 and the edge of the material clamped between the upper and lower clamping members as before described. The material having then been softened by the admission of steam to chamber A, the plunger 52 will be 115 depressed to force a block of the proper shape and size downward so as to press the central or crown portion of the material down through the opening of the size ring to shape the hat as shown in Fig. 10. Then 120 125 130

after the hat has been stretched to shape, the steam will be shut off and the air blasts turned on as before to cool and dry out the crown and brim portions of the hat. The 5 shape and size of the opening of the size ring will, of course, correspond to the shape and size of the head opening of the hat to be formed, and different rings will be provided for forming hats having head openings of different sizes and shapes. The plunger 52 10 will be adjusted on the plunger rod so as to cause the block to be depressed to the desired extent when the operating lever 53 is thrown down to be engaged by the catch 55, and the 15 lower projecting end of the plunger rod extending into a central opening in the block will serve to properly center the block. When a block having parallel sides to shape the crown of the hat with straight vertical 20 sides for a greater or less distance from the head opening is used, the same block may be used for forming hats with crowns of various heights simply by making the block of a height or depth sufficient for forming 25 the highest crowned hat desired and adjusting the plunger 52 so that the block will be projected downward into the opening in the size ring a greater or less distance, according to the desired height of the hat crown. 30 Obviously, the forming block may be simply pressed downward by the plunger or may be secured to and carried by the plunger, as desired. The shape of a hat such as may be produced with the machine used as shown in 35 Fig. 10 and with a block of the shape shown in that figure is shown in Fig. 14.

It will be understood that the invention is not to be limited to the exact construction shown and to which the foregoing description 40 has been mainly confined, but that it includes changes and modifications thereof within the claims, and that features of the invention may be employed independently of other features thereof and in machines 45 differing widely from that shown.

What is claimed is:

1. In a hat shaping machine, the combination of a steaming and setting chamber, shaping devices comprising holding means 50 for holding the edge of a hat body or blank with the crown portion and the main part of the brim portion thereof exposed to the interior of the chamber and means for stretching the material inward from the holding 55 means and about a crown form; means for supplying steam to said chamber during the shaping operation, and means for causing cool air to circulate through said chamber for setting and drying the shaped hat.
- 60 2. In a hat shaping machine, the combination of a steaming and setting chamber open on one side, a clamping member surrounding the open side of the chamber, means for clamping the edge of a hat body 65 or blank against said clamping member,

means for pressing a crown form into the central portion of the hat body or blank within the chamber, stretching means movable to cause the material to be stretched about the crown form and inward from the clamping means to shape the hat, means for supplying steam to said chamber, and means for causing a current of cool air to circulate through said chamber for setting and drying the shaped hat. 75

3. In a hat shaping machine, the combination of a steaming and setting chamber open on one side, a clamping member surrounding the open side of the chamber, means for clamping the edge of a hat body or blank against said clamping member, means for pressing a crown form into the central portion of the hat body or blank within the chamber, folding devices arranged to move inward over the outer face or base of the crown form to stretch the material over the form and inward from the clamping means to shape the hat and to form the head band, means for supplying steam to said chamber, and means for causing a current of cool air to circulate through said chamber for setting and drying the shaped hat. 80

4. In a hat shaping machine, the combination of a steaming and setting chamber open on one side, a clamping member surrounding the open side of the chamber, means for clamping the edge of a hat body or blank against said clamping member, means for pressing a crown form into the central portion of the hat body or blank within the chamber, folding devices arranged to move inward over the outer face or base of the crown form to stretch the material over the form and inward from the clamping means to shape the hat and to form the head band, 90 means for supplying steam to said chamber, and means for causing a current of cool air to circulate through said chamber for setting and drying the shaped hat. 95

5. In a hat shaping machine, the combination of a chamber open on one side, holding means for holding the edge of a hat body or blank with the central part of the body or blank extending into said chamber through the open side thereof, folding devices arranged to move inward over the outer face or base of a crown form which has been inserted into the central portion of the hat body or blank to stretch the material over the form and inward from the holding means to shape the hat and to form the head band, and means for causing a current of cool air to circulate through said chamber to set and dry the shaped hat. 105

6. In a hat shaping machine, the combination of a steaming and setting chamber open at one side, a clamping ring surrounding the 110

open side of the chamber, a second clamping ring movable to clamp the edge of a hat body or blank against the first said clamping ring, a plunger mounted to move with the second said clamping ring, means for giving the plunger additional movement to press a crown form into the central portion of the hat body or blank within the chamber, stretching means operable to cause the material of the hat body or blank to be stretched about the crown form and inward from the clamping rings to shape the hat, means for supplying steam to said chamber, and means for causing a current of cool air to circulate through said chamber for setting and drying the shaped hat.

7. In a hat shaping machine, the combination of a chamber open at one side, a stationary clamping ring surrounding the open side of the chamber, a movable clamping ring for clamping the edge of a hat body or blank against the stationary clamping ring, a plunger, a movable member by which the movable clamping ring and said plunger are carried, means for moving the plunger relatively to said member to press a crown form into the central portion of the hat body or blank within the chamber, stretching means operable to cause the material of the hat body or blank to be stretched about the crown form and inward from the clamping rings to shape the hat, and means for causing a current of cool air to circulate through said chamber for setting and drying the shaped hat.

8. In hat shaping machine, the combination of a steaming and setting chamber open at the top, a clamping ring surrounding the open top of the chamber, a cross head mounted to reciprocate vertically, a second clamping ring carried by the cross head, a crown form plunger carried by the cross head, means for giving the plunger an additional downward movement after the cross head has been moved downward to carry the second clamping ring into clamping position, folding devices mounted to move inward over the outer face or base of a crown form which has been pressed downward by the plunger, means for supplying steam to said chamber, and means for causing a current of cool air to circulate through said chamber for setting and drying the shaped hat.

9. In a hat shaping machine, the combination of a steaming and setting chamber, shaping devices for shaping a hat with the crown of the hat extending into said chamber, means for admitting steam to the chamber and for diffusing the steam in the chamber, and an air inlet and air outlet arranged adjacent to each other to cause a current of air to circulate through the chamber and about the crown of the shaped hat.

10. In a hat shaping machine, the combination of a steaming and setting chamber

having a curved side wall, shaping devices for shaping a hat with the crown thereof extending into the chamber, an air inlet for admitting a current of air to said chamber directed tangentially of the curved side wall thereof, and an air outlet adjacent to the air inlet.

11. In a hat shaping machine, the combination of a steaming chamber open at the top, a clamping plate surrounding the open top of the chamber, a removable clamping ring of yielding elastic material on said clamping plate, a clamping plate movable toward the first said clamping plate to clamp the edge of a hat body or blank against said clamping ring, and means for stretching the material of the hat body or blank inward from said clamping devices and about a crown form to shape the hat.

12. In a hat shaping machine, the combination of a steaming chamber open at the top, a clamping plate surrounding the open top of said chamber, a series of successively smaller removable rubber clamping rings arranged one within the other on said clamping plate, a movable clamping plate, and means for stretching the material of a hat body or blank the edge of which is held by said clamping devices inward from the clamping devices and about a crown form to shape the hat.

13. In a hat shaping machine the combination of a clamping plate, a series of successively smaller removable clamping rings arranged one within another on said plate to form an annular clamping face the inner dimensions of which may be changed according to the size of the hat body or blank to be shaped by removing one or more of the inner rings, means for positioning the outermost ring, means for clamping the edge of a hat body or blank against the innermost clamping ring on the clamping plate, and means for stretching the material of the hat body or blank inward from the clamping devices and about a crown form to shape the hat.

14. In a hat shaping machine, the combination of a clamping plate, a removable clamping ring on said plate, a movable clamping plate for clamping the edge of a hat body or blank against said clamping ring, and means for stretching the material of the hat body or blank held by said clamping devices inward from the clamping devices and about a crown form to shape the hat.

15. In a hat shaping machine, the combination of a steaming chamber having an open side, clamping means surrounding the open side of the chamber, means for adapting said clamping means for hat blanks or bodies of different sizes to engage only a narrow edge portion thereof, and means for stretching the material of the hat body or

blank held by said clamping means inward from the clamping means and about a crown form to shape the hat.

16. In a hat shaping machine, the combination of holding means for holding the edge of a hat body or blank, means for moving a crown form toward and through the plane bounded by said holding means, said means for moving the crown form 10 being adjustable to determine the position given to the crown form, and means for stretching a hat body or blank inward from the holding means and about the crown form to shape the hat.
- 15 17. In a hat shaping machine, the combination of a steaming chamber open at one side, holding means for holding the edge of a hat body or blank around the open side of said chamber, a plunger for pressing a 20 crown form into the open side of the chamber, said plunger being adjustable for determining the position given to the crown form, and means for stretching a hat body or blank held by said holding means inward 25 therefrom and about the crown form to shape the hat.

18. In a hat shaping machine, the combination of holding means for holding the edge of a hat body or blank, and means for 30 forcing an intermediate part of the hat body or blank inward over the outer face or base of a crown form to simultaneously stretch the brim portion of the material inward from the holding means and the crown portion 35 over the crown form to shape the hat and to form the head band.

19. In a machine for shaping hats, the combination of holding means for holding the edge of a hat body or blank, and means 40 for forcing an intermediate part of the body or blank inward over the outer face or base of a crown form and against a forming shoulder to stretch the brim portion of the material inward from the holding means 45 and the crown portion over the crown form, thereby shaping the hat and forming the head band.

20. In a hat shaping machine, the combination of holding means for holding the 50 edge of a hat body or blank, means for forcing an intermediate part of the hat body or blank inward over the outer face or base of a crown form to simultaneously stretch the brim portion of the material in- 55 ward from the holding means and the crown portion over the crown form to shape the hat and to form the head band, and means for subjecting the shaped hat to the cooling and drying action of a current of cool air 60 while it is held in shape by the shaping means.

21. In a hat shaping machine, the combination of holding means for holding the edge of a hat body or blank, means for forcing 35 an intermediate part of the hat body or

blank inward over the outer face or base of a crown form to simultaneously stretch the brim portion of the material inward from the holding means and the crown portion over the crown form to shape the hat and to form the head band, and means for causing currents of cool air to flow against the crown and against the brim of the shaped hat while it is held in shape by the shaping means. 70

22. In a hat shaping machine, the combination of holding means for holding the edge of a hat body or blank, means for subjecting the body or blank to the softening action of steam, means for forcing an intermediate part of the body or blank inward over the outer face or base of a crown form to stretch the brim portion of the material 80 inward from the holding means and the crown portion over the crown form to shape the hat and to form the head band, and means for subjecting the shaped hat to the cooling and drying action of a current of cool air while it is held in shape by the 85 shaping means.

23. In a hat shaping machine the combination of holding means for holding the edge of a hat body or blank, means for moving a crown form into a hat body or blank held by the holding means, and folding devices arranged to move inward over the outer face or base of the crown form to stretch the hat body or blank over the form and inward from the holding means to shape 90 the hat and to form the head band. 100

24. In a hat shaping machine, the combination of holding means for holding the edge of a hat body or blank, means for holding a crown form in position in a hat body or blank held by said holding means, and folding devices arranged to move inward over the outer face or base of the crown form to stretch the hat body or blank over the form and inward from the holding means to shape the hat and to form the 105 head band, said folding devices being adjustable for head bands of different sizes. 110

25. In a hat shaping machine, the combination of holding means for holding the edge of a hat body or blank, means for holding a crown form in position in a hat body or blank held by said holding means, a plurality of overlapping folding plates having folding edges extending in a direction inclined to the direction of movement 115 of the plates, and operating means for moving said plates inward over the outer face or base of the crown form to stretch the hat body or blank over the form and inward from the holding means to shape the hat 120 125 and to form the head band.

26. In a hat shaping machine, the combination of holding means for holding the edge of a hat body or blank, means for holding a crown form in position in a hat 130

body or blank held by said holding means, a plurality of overlapping folding plates having folding edges extending in a direction inclined to the direction of movement of the plates, operating means for moving said plates inward over the outer face or base of the crown form to stretch the hat body or blank over the form and inward from the holding means to shape the hat and to form the head band, and adjusting means for varying the inward movement of the folding plates.

27. In a hat shaping machine, the combination of holding means for holding the edge of a hat body or blank, means for holding a crown form in position in a hat body or blank held by said holding means,

oppositely arranged and overlapping folding plates each having folding edges *a* and a folding and shaping edge *b* and operating means for moving said folding plates inward over the outer face or base of the crown form to stretch the hat body or blank over the form and inward from the holding means to shape the hat and to form the head band.

In testimony whereof, I have hereunto set my hand, in the presence of two subscribing witnesses.

LESLIE STEVENS.
